UNITED STATES PATENT OFFICE.

JOHN M. BRYANT, OF MINNEAPOLIS, MINNESOTA.

TRACE-HOLDER.

SPECIFICATION forming part of Letters Patent No. 738,882, dated September 15, 1903.

Application filed May 19, 1902. Renewed February 21, 1903. Serial No. 144,525. (No model.)

To all whom it may concern:

Be it known that I, JOHN M. BRYANT, a citizen of the United States, residing at Minneapolis, in the county of Hennepin and State 5 of Minnesota, have invented certain new and useful Improvements in Trace-Holders; and I do hereby declare the following to be a full, clear, and exact description of the invention, such as will enable others skilled in the art to 10 which it appertains to make and use the same.

My present invention has for its object to provide an improved trace-holder; and to this end it consists of the novel devices and combinations of devices hereinafter described, 15 and defined in the claims.

The invention is illustrated in the accompanying drawings, wherein like characters indicate like parts throughout the several views.

20 Figure 1 is a plan view, with some parts broken away, showing a portion of a whiffletree and a trace or tug held together by one of my improved trace-holders. Fig. 2 is a section on the line $x^2 x^2$ of Fig. 1. Fig. 3 is a section on the line $x^3 x^3$ of Fig. 1. Fig. 4 is a view corresponding to Fig. 1, but illustrating a slightly-modified construction; and Fig. 5 is a section on the line $x^5 x^5$ of Fig. 4.

25 The character *a* indicates the whiffletree and the character *b* a trace or tug of an ordinary harness. At its ends the whiffletree *a* is perfectly smooth and is slightly tapered, and the trace *b* is provided with one or more eyes or slits *b'*, which adapt the trace to be slipped 30 onto the end of the whiffletree *a*, as shown in the drawings.

35 My improved trace-holder is formed from a single piece of stiff spring-wire, which at its intermediate portion is bent to form a loop *f* (preferably rectangular in form) and has its ends overlapped and projected to form prongs *f'*, which are again bent laterally to form spring clamping-fingers *f²*, which are adapted to embrace and yieldingly clamp 40 the end portion of the whiffletree *a*. In the construction illustrated in Figs. 1, 2, and 3 the spring clamping-fingers *f²* are bent, the one upward and the other downward, to 45 form alined trunnions *f³*, which are inserted 50 ed into a perforation or seat *a'* in the said whiffletree, as best shown in Fig. 2. By reference to said figure it will be noted that the

said trunnions *f³* do not come together, but terminate short of each other, so as to permit the so-called "clamping-fingers" *f²* always to 55 yieldingly press against and clamp the whiffletree, and thereby prevent rattling of the holder. This antirattling feature is important.

The construction illustrated in Figs. 4 and 60 5 is the same as that above described, except that one of the spring-fingers *f²* is provided with a long trunnion *f⁴*, which projects through the perforation or seat in the whiffletree and is passed through an eye *f⁵* in the 65 other spring-finger *f²*. In this construction the antirattling feature is also present, since the spring-fingers *f²* are again left free for clamping engagement with the whiffletree under the spring tension from the spring- 70 prongs *f'*.

In both of the forms of holder illustrated all bolts, nuts, rivets, and other separable devices for coöperation with the holder to hold the same in working position are dispensed 75 with, and while the holder is securely held in working position it may be very quickly applied or removed. As is obvious, the device is of extremely small cost.

The manner of using the device is clearly 80 illustrated in the drawings, and it is evident that when the trace is passed through the loop *f* of the holder and forced onto the end of the whiffletree the strain on the tugs will keep the holder in the position shown in Fig. 85 1, and the holder while in this position will prevent the trace from being moved, either accidentally or otherwise, off from the end of the whiffletree. On the other hand, it is evident that when the trace is given slack and 90 bent, as indicated by dotted lines in Fig. 1, the holder may be moved into its dotted-line position, and the trace may then be easily forced off from the end of the whiffletree.

This form of holder renders unnecessary 95 the cutting or notching of the whiffletree at that reduced portion which is engaged by the trace, and thus gives to the trace its maximum strength for a given amount of material contained therein.

100 In view of the fact that the spring clamping-prongs *f'* are overlapped or crossed it is evident that any strain tending to elongate the loop *f'* will cause the said clamping-prongs

f' to more tightly clamp the end of the whiffle-tree, whereas if the said prongs were not crossed such strains would tend to throw them out of engagement with the whiffle-tree.

5 What I claim, and desire to secure by Letters Patent of the United States, is as follows:

1. A trace-holder provided with a loop or eye through which the trace may be passed and provided with overlapped or crossed spring 10 clamping-prongs engageable with the whiffle-tree and pivotally connected thereto, substantially as described.

2. A trace-holder formed from a single piece of spring-wire bent to form a loop f through 15 which the trace may be passed and having its ends extended and overlapped or crossed to form spring clamping-prongs f' adapted to

embrace the whiffle-tree with a clamping action, and provided at their ends with means for pivotally connecting them to the whiffle-tree, substantially as described. 20

3. A trace-holder formed from a single piece of spring-wire bent to form a loop f with overlapped or crossed spring clamping-arms f' f'' , the one arm-section f'' having a trunnion f^4 , 25 and the other having the eye f^5 through which said trunnion works, substantially as described.

In testimony whereof I affix my signature in presence of two witnesses.

JOHN M. BRYANT.
